INVENTOR.

UNITED STATES PATENT OFFICE.

GEORGE WOOD, OF PROVIDENCE, RHODE ISLAND.

DESIGN FOR A CUFF-BUTTON.

SPECIFICATION forming part of Design No. 33,016, dated July 31, 1900.

Application filed June 27, 1900. Serial No. 21,857. Term of patent 3½ years.

To all whom it may concern:

Be it known that I, GEORGE WOOD, a citizen of the United States, residing at Providence, in the county of Providence and State 5 of Rhode Island, have invented and produced a certain new and original Design for Cuff-Buttons, of which the following is a specification, reference being had therein to the accompanying drawings.

10 Figure 1 is a side view of my button, and Fig. 2 is a vertical sectional view of the same.

As shown in the drawings, the leading or material feature of my design consists of an angular body with two ornament-plates on 15 the opposite sides thereof and in detail may be described as follows: The button is a generally-triangular figure having an arched apex *a* and slightly-diverging sides *a' a'*.

Near their respective ends the sides are inwardly directed, *a'' a''*, until they nearly contact with each other and terminate in two balls *c c*. Thin plates *b b* ornament the sides *a' a'* and lie in corresponding planes, each projecting below the terminal bends of the button-body.

Having thus described my invention, what I claim as new, and desire to secure by Letters Patent, is—

The design for a cuff-button as herein shown and described.

In testimony whereof I have affixed my signature in presence of two witnesses.

GEORGE WOOD.

Witnesses:

GEO. D. HERSEY,

HORATIO E. BELLOWES.
